FIG. 14

A technical drawing of a film strip. The strip is oriented vertically and features several circular markings with numbers inside. From top to bottom, the markings are: 29, 331, 36, 19, 321, 331, 34, 19, 30, 36, and 35. The numbers 19 and 30 appear to be repeated. The markings are arranged in two columns: a left column with 29, 19, 19, and 30; and a right column with 331, 36, 321, 331, 34, 36, and 35. The film strip has a vertical line on the left and a vertical line on the right, with horizontal lines connecting the markings.

UNITED STATES PATENT OFFICE.

JOHN G. JONES, OF ROCHESTER, NEW YORK, ASSIGNOR TO EASTMAN KODAK COMPANY,
OF ROCHESTER, NEW YORK, A CORPORATION OF NEW YORK.

CONSECUTIVE-PRINTING APPARATUS.

1,326,062.

Specification of Letters Patent. Patented Dec. 23, 1919.

Application filed May 24, 1918. Serial No. 236,396.

To all whom it may concern:

Be it known that I, JOHN G. JONES, a citizen of the United States of America, residing at Rochester, in the county of Monroe and State of New York, have invented 5 certain new and useful Improvements in Consecutive-Printing Apparatus, of which the following is a full, clear, and exact specification.

10 This invention relates to apparatus for printing on sensitive photographic material, and more particularly to apparatus for light-printing consecutive symbols thereon.

The general object of my invention is to 15 provide an improved broad combination of elements, as well as certain improved sub-combinations, which will operate accurately, rapidly, reliably, and efficiently on large-scale commercial work. Another object of 20 my invention is to provide apparatus in which the sensitive material is protected against injury from stray light or abrasion; in which numbers are printed onto the material in progressively decreasing order so 25 that, when the numbered material is wound up, the lowest numbers will be on the outside of the roll; in which a novel lighting system is provided including reflecting devices for properly directing the beams of light; in 30 which printing members of novel construction are employed together with operating mechanism, permitting them to be independently, manually and rapidly adjusted to their zero or starting positions; in which an 35 improved shutter is embodied; in which a movable presser-foot is so actuated as to positively press the sensitive material toward the printing members; in which the speed of operation of the shutter and 40 presser-foot can be varied; and in which the several parts are all driven in properly timed relation. Further objects will herein-after appear.

My invention at present finds its most important application in the printing of consecutive numbers, at regular intervals along one edge of unexposed motion picture negative film, and I shall describe a preferred embodiment of my invention which is adapted for that purpose, but my invention is not confined to that particular branch of the

printing art except as indicated in the appended claims.

In the accompanying drawings:

Figure 1 is a side elevation of apparatus 55 embodying my invention, certain parts being broken away upon the line 1-1 of Fig. 2;

Fig. 2 is a diagrammatic perspective view showing my invention in connection with a 60 film perforating machine;

Fig. 3 is an end elevation of the apparatus with the film feed rollers and certain connected parts broken away;

Fig. 4 is a fragmentary plan view of the 65 numbering device, light chamber and associated parts;

Fig. 5 shows in end elevation a combined 70 ratchet and cam wheel forming part of the driving mechanism;

Fig. 5^A is a side elevation of the same parts;

Fig. 6 is a fragmentary end elevation of 75 part of the driving mechanism;

Fig. 7 is a similar view showing the parts 75 in altered position;

Fig. 8 is a fragmentary end elevation of 80 part of the driving mechanism and the presser foot, certain parts being broken away;

Fig. 9 is an elevation of a lamp unit used in the illuminating system;

Fig. 10 is a detail longitudinal section 85 through the dashpot retarding mechanism;

Fig. 11 is a longitudinal sectional view on the line 11-11 of Fig. 1;

Fig. 12 is a detail perspective view of a 90 mirror used in the illuminating system;

Fig. 13 is a fragmentary sectional view on an enlarged scale of a part of the illuminating system with adjustments taken upon the same line as the section in Fig. 11;

Fig. 14 is a plan view of the shutter element;

Fig. 15 is a transverse sectional view taken 95 upon the line 15-15 of Fig. 11;

Fig. 16 is a side elevation of one of the numbering elements;

Fig. 17 is a side elevation of a flanged gear upon which the numbering element is supported, as indicated in dotted lines;

Fig. 18 is a transverse detail sectional

view of part of the illuminating system taken upon the line 18—18 of Fig. 11;

Fig. 19 is a detail sectional view upon an enlarged scale taken upon the line 19—19 5 of Fig. 16;

Fig. 20 is a fragmentary view of numbered motion picture film, the latent images being shown in full lines for the sake of clearness;

10 Figs. 21, 22 and 23 are side elevations of mechanical elements which are assembled in the numbering mechanism;

Fig. 24 is an end elevation of the element shown in Fig. 23;

15 Fig. 25 is a fragmentary perspective view of a group of driving pawls used in the numbering mechanism;

Fig. 26 is a side elevation of part of the operating devices for the numbering mechanism;

20 Fig. 27 is a fragmentary perspective view of a group of stop pawls;

Fig. 28 is a transverse sectional view taken on the line 28—28 of Fig. 26;

25 Fig. 29 is a similar view showing the same parts in altered position.

My invention is particularly convenient when used in connection with a machine for perforating the edges of motion picture film, and I have, therefore, illustrated it 30 in such connection, but it is understood that it may be used alone or with any machine which advances the film in proper relation to the movement of the rest of the apparatus. In Fig. 2 I have shown in unshaded perspective a Bell and Howell film perforating machine A which is typical of such perforators, upon which is mounted my apparatus denoted generally by B. In the perforator the film passes from a supply reel 1 over idlers 2 and driving wheel 3 through the apparatus B beneath the punches 4 35 through pads 5, over sprocket 6 and idlers 7 to winding reel 8. In the bed 9 of the 40 perforator is an intermittent film feed of standard type moving in timed relation to the continuously rotating sprocket 6 and wheel 3. The latter wheel and its idlers 2 are cut away as shown in Fig. 1 to avoid 45 contact with the sensitive face of the film.

A shaft 10 which carries wheel 3 is used to support the main frame 11 of my apparatus. The frame is supported on the shaft 10 by bearings 12 at each side of a gear box 55 13 on the perforator. As shown in Fig. 1, shaft 10 is driven from cross shaft 14 of the perforator through beveled gears 16, shaft 14 being located in hollow arm 15.

Since the frame 11 can swing about shaft 60 10, it is necessary to provide a device which will hold it in adjusted position. Accordingly, I attach a sector plate 17 to the side of gear box 13, the plate having spaced perforations 18 in which is received the end

of a sliding pin 19 on frame 11. The apparatus normally rests in the position shown in Figs. 1 and 2, but if it is desired to perforate the film without numbering it, pin 19 is removed from the lower opening 18 and the apparatus swung upwardly until 70 19 can be inserted in the upper hole 18.

The film after leaving wheel 3 passes in a loop 20 to the pathway of my apparatus, best shown in Figs. 4 and 15. This pathway comprises plates 21 having narrow supports 75 22 at each side for engaging the edges only of the film. The central portion of plates 21 is depressed at 23 so as to be out of contact with the sensitive surface of the film and particularly the picture areas thereof. 80 Of course, the sensitive surface of the film is downward toward the light printing opening 24 formed in one side of the pathway in line with one of the supports 22. The entire apparatus is used in a dark room 85 and the only actinic light which can affect the film issues internally through opening 24 from the illuminating system, hereinafter described. Consequently, the pathway shields all of the film from light action except a narrow section at one edge which lies 90 outside the picture areas. The depression of the central portion 23 is generally sufficient to avoid abrasion of the film, but as an additional precaution in my preferred device I mount centrally of the plates 21 a series of rolls 25 which give practically 95 frictionless support to the center part of the film. Lateral guides 26 are screwed on to the edges of plates 21, as indicated in Figs. 4 and 15. In one of the supports 22 I may also form an additional opening 27 receiving a stationary plate 28 bearing a light transmitting image or word which will be impressed upon the film at each 100 printing operation.

In the opening 24, however, I provide a series of relatively movable printing members or elements 29 each bearing a set of images of the symbols or numerals to be printed. These elements are in tubular or ring form and are provided with peripheral plane facets 30 best seen in Figs. 16 and 19. Leading to alternate facets, are radial openings 31 in which are located plates 32 bearing light transmitting images 321, either negative or positive, of numerals or other symbols to be printed. Alternating with these light transmitting images are plates 33 bearing observation images 331, duplicating or corresponding to images 321, but regularly spaced therefrom. Thus, in the preferred form of my apparatus each observation numeral is spaced about 90° around the ring from the corresponding light transmitting printing numeral. See, for example, numeral 2 in Fig. 16. These observation images are opaque in my preferred form. 115 120 125

Rings 29 are mounted on flanges 34 of gears 35, the flanges being perforated at 36 in alinement with openings 31. These assembled gear and ring units are co-axially mounted upon a tubular bearing 37 (Fig. 11) provided upon its upper portion in alinement with opening 24 with a set of light transmitting areas or perforations 38 these perforations being of a size and location to aline with selected openings 36 and 31 in the gear flanges and rings. The bearing, and therefore the axis about which the tubular members turn, is substantially parallel to the path of movement of the film, and, consequently, the printing members 29 move in planes which extend laterally or transversely of the pathway of the film.

Each element 29 is driven by its individual gearing. Upon shaft 39, below and parallel to bearing 37, are rotatably mounted a series of gears 40, one meshing with each gear 35. Shaft 39 is supported in bearings 391. Attached to each gear 40 is a ratchet wheel 41 for driving the same. Upon the opposite side of each gear 40 is attached a pawl shield 42 having a single depressed portion 43, best seen in Fig. 23.

A yoke 44 is fastened on shaft 39 to oscillate therewith and carries upon a transverse rod 45 a series of pivoted pawls 46 for driving ratchets 41, said pawls being pressed toward said ratchets by springs 47 held in place on yoke 44 by plate 48. All the pawls 46 which enter between the gears 40 are of sufficient width to simultaneously engage both a ratchet 41 and pawl shield 42. The tail 49 of each pawl 46 carries a short rod 50 which engages in a depressed portion 51 in the tail of the next adjacent pawl (see Fig. 25), thus forming a direct connection between them. At one side of shaft 39 is a stationary rod 52 upon which are pivotally mounted a series of retaining pawls 53 which are pressed by springs 54 against the ratchets 41 to prevent the latter from turning backward or clockwise in Fig. 28, said ratchets have special sockets 55 into which the noses of pawls 53 drop, so that the images on rings 29 will be in exact alinement in opening 24 and so that the corresponding facets will be substantially in the same plane.

In the illustrated preferred form, each ring bears a set of numerals, 0 to 9 inclusive. At the start the 0's may be alined as shown in Fig. 4, or the 9's may be alined in case the apparatus is set to operate the printing members from the highest number downward, such a setting being effected by reversing the rings 29 on flanges 34. The latter arrangement has the advantage that the numbers which are printed upon the edge of the film (at one foot intervals, for example, if the feed is adjusted for that spac-

ing) will decrease consecutively down to 1, thus bringing the smallest numeral upon the outside of the film roll and avoiding the necessity of either rewinding it or using the numbers backward.

When the desired starting numerals are in alinement in opening 24, the plane facets 30 being also substantially flush with the surface of support 22, the pawl shields 42 will be so positioned that the depressed portions 43 are just beyond the operative strokes of pawls 46. Each ratchet wheel is provided with 10 teeth, thereby requiring 10 operative impulses from its pawl to turn it step-by-step through the standard distance to change the numerals.

Every time that the yoke 44 makes a working stroke, the left hand pawl 46 in Fig. 26 will drive its ratchet through a step corresponding to one tooth. Through gears 40 and 35, the first ring 29 will be correspondingly moved to present a different numeral in opening 24. During each of the first nine strokes, the remaining pawls 46 will ride upon the curved faces of shields 42 and so cannot engage their corresponding ratchets 41, being thus retained in inoperative position. Upon the tenth stroke, the depressed portion 43 of the first or left hand pawl shield 42 will come beneath the second pawl 46 and thus the latter can enter the second ratchet 41 and advance it one step, thereby changing the corresponding numeral on the second ring 29. During the eleventh stroke, the depressed portion 43 of the first pawl shield 42 will be moved out of reach of the second pawl and the latter will idly reciprocate until said first shield 42 has again been advanced ten steps. When the hundredth actuation takes place, the second gear 40 and its attached pawl shield 42 will have moved through ten steps, (one step at the tenth, twentieth, thirtieth, etc., strokes) thereby bringing the depressed portion of the second shield 42 into the path of the third pawl 46 and permitting the latter to operate the third ratchet through one step, thus changing the numeral on the third ring 29.

During the hundred and first to the hundred and ninth strokes, the depression 43 of the second pawl shield will remain beneath the second pawl 46 so the latter, if unrestrained, could rotate the third ratchet at each stroke. This is due to the fact that the second gear and consequently the second shield is moved only one step at every tenth stroke. Clearly, if the third pawl could thus drive the third gear at every stroke from the hundred and first to the hundred and ninth, the necessary consecutive numbering would not take place. To guard against this, pins 50 are provided. Each pin holds the next adjacent pawl in inoperative

position so long as its own pawl remains in inoperative position. Consequently, the pin on the second pawl 46 will hold the third pawl in inoperative position from the hundred and first to the hundred and ninth stroke, said second pawl being itself held inoperative by the first pawl shield. By extending this analysis it will be found that the pawl shields 42 and the pins 50 together insure that all the numbers will appear in opening 24 in consecutive order.

The numbering devices hereinabove described are contained in a chamber 56 having a movable rear cover 57 and two openings 58 and 59 in its front plate 60, the latter also being removably held in place by screws. Opening 58 is located laterally of the bearing 37, as best indicated in Figs. 3 and 15, and is closed by a transparent window 61 through which may be observed an aligned set of observation numerals 331 which are duplicates of the corresponding printing numerals 321 which appear at the same time in opening 24, the two sets of numerals being spaced for this purpose as hereinabove stated.

It will be noted that the teeth on ratchet 41 as well as the sockets 55 and the co-operating pawls 46 and 53 are all so shaped that the ratchets together with their attached parts are driven unidirectionally. They are also independently and manually movable in this one direction. The construction is such that each gear 40 may be turned by hand, pawls 46 and 53 slipping from tooth to tooth and socket to socket during such manipulation. In this way a fractional rotation of each gear 40 and consequently of each ring 29 suffices to quickly set the whole apparatus back to zero or starting position. Opening 59 permits the operator to introduce a tool for such manipulation. It is normally closed by a pivoted door 62.

Inside the tubular bearing 37 is a tubular shutter 63 provided with longitudinal slots 64 and 65 designed to come successively into alignment with perforations 38 in bearing 37 which are themselves in line with openings 24 and 27 in plates 21. The opaque portions between the slots are located below perforations 38, when the shutter is stationary, so as to prevent all light from passing to the printing numerals. The shutter is mounted upon a rotary hub 66 which turns with shaft 67 in a bearing 68 at one side of the chamber 56. It is driven intermittently in one direction to move a slot at each step across perforations 38 so that a flash of light from the lamp hereinafter described can pass through the printing images to the film.

Inside of shutter 63 is a stationary tube 69 (Fig. 18) which is supported in an end wall of the chamber 56. Within this tube is

stationarily fastened a block 70 provided with a series of staggered faces 71, each inclined to the axis of the tube and bearing a corresponding small inclined mirror 72, the angle of which may be adjusted if desired by means of screws 73, as shown in Fig. 13. The upper side of the tube is cut away at 74 so as to pass light to the perforations 38 and printing images of rings 29, which are situated in pathway 24.

While in the broader aspects of my invention any means for directing actinic light to mirrors 72 may be employed, I prefer to use a light source in a light-tight casing which is offset from the path of the film so as not to interfere with the latter. Thus in the drawings, I have shown a casing 75 located at one side of chamber 56 and provided with an opening 76 in the top thereof which connects with said chamber, there being mounted detachably in said casing a small incandescent lamp 77 carried by a removable socket member 78 of well known type. Beneath the lamp 77 I may also employ a concave mirror 79 to direct some of the rays from lamp 77 upwardly. In one wall of chamber 56, and forming a part thereof, is detachably fastened an inclined mirror 80, a black mask or gasket 81 being located between it and the surrounding walls of 60. Mirror 80 is substantially parallel to mirrors 72 and inclined to the axis. Consequently, the beams of light from lamp 77 which proceed upwardly through opening 76 are directed by mirror 80 on to the staggered series of mirrors 72 which are so spaced and dimensioned as to send a separate beam toward each perforation 38 and the corresponding images 321 beyond.

From consideration of this structure, it will be seen that no actinic light can leak out of the apparatus and none can reach the window 58, the opaque sides of tube 69 preventing any such spreading of the rays. In order to show whether the lamp is functioning properly, I provide a small aperture 136 in one wall of the casing covered by a sheet of material which is transparent and emits only non-actinic or deep red light.

In order that the edge of the film to be printed may be held in proper printing contact with the facets and image bearing plates 32 of rings 29, I provide a presser foot 82, see Figs. 3, 4 and 8. This is mounted to oscillate with shaft 83 which is carried in bearings 84 upon one wall of chamber 56, shaft 83 being shown as substantially parallel to the path of movement of the film through the apparatus. A spring 85 tends to turn shaft 83 to bring the presser foot 82 in its upper position, and means hereinafter described are employed to move it positively in the opposite or clamping position. Upon one end of shaft 83 is an oscillating

arm 86 in which is a retractable pin 87 which engages with an independently pivoted part 88 of the presser foot. By retracting pin 87 part 88 is no longer driven by arm 86 and 5 can be independently swung out of the way to permit access to opening 24 in the pathway.

The movable parts of the entire apparatus hereinabove described are driven in proper 10 timed relation by mechanism which will now be detailed. Shaft 10 (Fig. 1) is connected by beveled gears 89 with a shaft 90 which, through beveled gears 91, rotates a stub shaft 92 turning the cam 93 thereon. Sliding 15 upon shaft 92 is the slotted block 94, Fig. 10, the lug 95 on which engages the driving periphery of cam 93, said periphery having a gradually rising face 96 and a sudden radial drop shoulder 97. Block 94 is drawn toward 20 the cam by a strong spring 98. Attached to block 94 and moving therewith is a link rod 99 formed in two parts, said parts being adjustably connected by a turnbuckle 100 to permit the total length to be changed. This 25 enables the parts of the pawl and ratchet mechanism hereinafter described to be properly adjusted. Rod 99 carries attached thereto the piston 101 of dash-pot 102, the latter being held stationary by a yoke 103 30 adjustably clamped upon pin 104 by means of split bearing 105 and bolt 106. The yoke engages the dash-pot by means of slots 107 and pins 108. The dash-pot is provided with an end 109 containing a series of perforations 110 which may be moved into and out of registry with perforations 111 in the body of the dash-pot, the end 109 turning relative to the body of the dash-pot upon hub 112, and being held in adjusted relation by means 35 of screw 113 engaging in groove 114 of said hub. In Fig. 10, the perforations 110, being partially out of alinement with 111 intersect the section plane only slightly and so form small horizontal slots 115 in said view. 40 The outer end of rod 99 is connected through a yoke 116 and pin 117 with a lever 118 which oscillates shaft 392, the latter being supported by an additional bearing 119 outside of the lever 118. On the outer end of 45 shaft 392 and oscillating therewith is an arm 120 which is provided with a slot 121 engaging a pin 122 by means of which it oscillates sector 123 which is freely rotatable upon the outer end of shaft 67. On the inner end of 50 shaft 392 and oscillating therewith is an arm 393, Fig. 11, provided with a radial slot 394 near one end, in which engages a pin 395 on yoke 44.

The sector 123 carries a small pawl shaft 55 124 which is constantly turned by means of spring 125 to press its pawl 126 into working engagement with ratchet wheel 127. A stop pawl 128 is pushed by spring 129 against ratchet wheel 127 to prevent the

same from turning backward or clockwise 65 in Figs. 6, 7 and 8. The ratchet wheel 127 is connected to a cam wheel 130 by means of parallel spaced pins 131, there being one pin for each tooth of the ratchet wheel. The cam is provided with a series of high 70 spots 132, one high spot being located angularly between each pair of teeth, as shown in Fig. 5. The ratchet wheel 127 and cam 130 are attached to shaft 67 to rotate therewith. The end of shaft 83 carries an operating arm 133 which bears at its lower end a roller 134 engaging the periphery of cam 130, the shape of the cam being such that a rapid oscillation will be given arm 133 during each step through which the cam 130 is 80 rotated.

The ratchet wheel 127 and the parts attached thereto are given a rapid movement at each step. In order that this quick turn may not be extended too far, due to the momentum of the parts, I provide a positive stop for limiting the movement. The lever 118 is provided with an extension 135 which 85 springs into engagement with one of the pins 131 at each stroke, thereby positively 90 and accurately ending the movement.

The operation is as follows:

The unperforated film being threaded through both the apparatus and the perforator in the dark-room, and the lamp 77 being lighted, the parts are set in motion. The perforating machine A will draw the film intermittently through the apparatus B. Since shaft 14 is connected to turn in timed relation to such feeding means and since 95 cam 93 is connected through the above described gearing and shafts with shaft 14, said cam 93 will turn in timed relation with the forward movement of the film. Cam 93, beginning with the position in Fig. 1, moves 100 rod 99 forwardly on to the right, thereby oscillating shaft 39 and swinging yoke 44 to operate the train of pawls, ratchets, and gears which change the printing numbers appearing at the printing station or opening 105 110 24. This forward movement of 99 and oscillation of lever 118 also swing extension 135 out of locking position. This movement takes place preferably during the advance 115 of the film through a standard distance, say one foot.

At an instant when the film has stopped, or there is a "dwell" in its movement, the lug 97 slips off from the high point of cam 93 so that block 94 and rod 99 are pulled suddenly backward to the left in Fig. 1 by spring 98, the dash-pot 102 controlling the speed of the return and cushioning the action. This causes shaft 39 to oscillate in the other direction, moving arm 120 clockwise 120 125 in Fig. 6, thereby oscillating sector 123 and, through pawl 126, advancing the ratchet 127 to the extent of one tooth, ex-

6 tension 135 being brought to the locking position indicated in Fig. 8. The advance of ratchet 127 to the extent of one tooth rotates shaft 67 sufficiently to bring a slot in the 5 shutter 63 past the perforations 38 in tube 37, thereby permitting a flash of printing light to pass to those printing images 321, which are located in alinement with opening 24. At approximately the same time that 10 the shutter is being thus actuated, the high part 132 of cam wheel 130 will press arm 133 outwardly, thereby rocking shaft 83 and pushing presser foot 82 positively downward to press or clamp the film against the 15 printing characters. This insures a clear image which results from proper printing contact during exposure. At the end of the short twist given to ratchet 127 and cam 130, the roller 134 will ride off high part 20 132, thereby releasing the presser foot which moves upwardly under the influence of the spring 85. The shutter will then be in the position where it cuts off all light rays from the printing images. This cycle of operations 25 is repeated at each reciprocation of rod 99 and consequently a series of consecutive latent images will be printed at proper intervals along the edges of the film strip 141, Fig. 20. While the location of the latent 30 images, which are thus impressed upon the film, is not of primary importance in the broader aspects of my invention, provided such images do not fall within the picture areas; nevertheless I prefer to place 35 the numbers along an edge of the film where they will remain unaffected by the subsequent perforating operation. My apparatus is, of course, adaptable for use with film which is not perforated, any of the well known feeding devices for advancing such 40 film being employed.

Having thus described my invention, what I claim and desire to secure by Letters Patent of the United States, is:

45 1. In a photographic printing apparatus, a pathway for the film, said pathway having a printing opening therein, means for sending actinic light intermittently toward said opening, printing elements movable relative to each other and also movable between said means and said pathway, said pathway including a shield for excluding said light from the picture areas of the film.

50 2. In a photographic printing apparatus, a pathway for the film, said pathway having a printing opening therein, means for sending actinic light intermittently toward said opening and printing elements movable relative to each other and adjacent said pathway in planes transverse to the pathway.

55 3. In a photographic printing apparatus, a pathway for the film, said pathway having a printing opening therein, means for sending actinic light intermittently toward said

opening, and printing elements movable relative to each other and adjacent the pathway and rotatable about axes parallel to the direction of movement of the film along said pathway.

65 4. In a photographic printing apparatus, a pathway for the film, said pathway having a printing opening therein, means for sending actinic light intermittently toward said opening, and printing elements comprising light transmitting images movable relative to each other and across said opening adjacent the pathway, said pathway including a shield for excluding said light from the picture areas of said film.

70 5. In a photographic printing apparatus, a pathway for the film, said pathway having a printing opening therein, means for sending actinic light intermittently toward said opening, printing elements movable relative to each other and also movable between said means and said pathway, said pathway including a shield for excluding said light from the picture areas of the film, and driving mechanism for operating said means and elements in timed relation.

75 6. In a photographic printing apparatus, a pathway for the film, said pathway having a printing opening therein, means for sending actinic light intermittently toward said opening, printing elements movable relative to each other and adjacent said pathway in planes transverse to the pathway, and driving mechanism for operating said means and elements in timed relation.

80 7. In a photographic printing apparatus, relatively movable tubular printing members, each comprising a set of light transmitting images of symbols to be printed.

85 8. In a photographic printing apparatus, relatively movable tubular printing members, each comprising light transmitting images of symbols to be printed and observation images of said symbols, said observation images being regularly spaced from the corresponding light transmitting images.

90 9. In a photographic printing apparatus, a chamber having a printing opening and an observation window in the walls thereof, printing members each mounted in said casting to move past said opening and said window, each member comprising light transmitting images of symbols to be printed and auxiliary images of said symbols, said auxiliary images being regularly spaced from said light transmitting images to bring opposite the observation window an auxiliary image which corresponds to the light transmitting image which is opposite the printing opening.

100 10. In a photographic printing apparatus, a tubular bearing having light transmitting areas in the wall thereof and a plurality of relatively movable tubular printing mem-

bers, each comprising a set of light transmitting images of symbols to be printed, said members being movably mounted on said bearing to bring said images successively over said areas.

11. In a photographic printing apparatus, a tubular printing element provided with a series of openings, each opening containing a light transmitting plate bearing an image 10 of a symbol to be printed.

12. In a photographic printing apparatus, a printing ring provided with a series of plane peripheral facets and with openings therethrough leading to said facets, each 15 opening containing a light transmitting image of a symbol to be printed.

13. In a photographic printing apparatus, a printing element comprising a gear provided with a flange, a ring on said flange, 20 said ring and flange having aligned openings and images of symbols to be printed located in said openings.

14. In a photographic printing apparatus, a series of relatively movable tubular elements, each comprising a set of light transmitting images of symbols to be printed, devices for advancing each element step-by-step through a complete movement, and means controlling said devices to advance an 25 element a step upon the completion of movement of the next adjacent element of the series.

15. In a photographic printing apparatus, a series of relatively movable printing elements each bearing a set of images to be printed, a series of driving devices, there being a device for each element, mechanism for operating said driving devices, and controlling means for said driving devices, except the first of the series for restraining each device from driving its element until the next element on the side toward the first 40 of the series has moved through a standard distance.

16. In a photographic printing apparatus, a series of relatively movable printing elements, each bearing a set of images to be printed, an operating mechanism for each element, each mechanism including a set of 45 driving and driven members movable into and out of driving relation, means for actuating each driving member, and a series of devices for preventing driving relation between the driving and driven members of any set until the next adjacent set has operated through a standard distance, the devices for any set of members being controlled from both the driving and driven members of the next adjacent step.

17. In a photographic printing apparatus, a series of relatively movable printing elements, each bearing a set of images to be printed, an operating mechanism for each element, each mechanism including a set of 50

driving and driven members movable into 65 and out of driving relation, means for actuating each driving member, and a series of devices for preventing driving relation between the driving and driven members of any set until the next adjacent set has operated through a standard distance, the devices for any set of members being controlled from the driving member of the next adjacent set.

18. In a photographic printing apparatus, 70 a series of relatively movable printing elements, each bearing a set of images to be printed, an operating mechanism for each element, each mechanism including a set of driving and driven members movable into 75 and out of driving relation, means for actuating each driving member, and a series of devices for preventing driving relation between the driving and driven members of any set until the next adjacent set has operated through a standard distance, the devices for any set of members being controlled from the driven member of the next adjacent set.

19. In a photographic printing apparatus, 80 a series of relatively movable printing elements, each bearing a set of numerals, a series of ratchets, there being a ratchet connected with each element to move the latter, a series of driving pawls, there being one 85 pawl for each ratchet, each pawl being movable to a ratchet-driving position and to an inoperative position, a series of pawl shields connected with said ratchets, the pawl shield of each ratchet holding the pawl, which 90 drives the next adjacent ratchet, in its inoperative position until the first named ratchet has driven its connected element through a standard distance, a direct connection between each pawl and the next pawl, said 95 connection holding said next pawl in inoperative position while said first named pawl is in its inoperative position, and means for actuating said pawl.

20. In a photographic printing apparatus, 100 relatively movable tubular printing members, each comprising a set of light transmitting images of symbols to be printed, and means for supporting sensitive material 105 in co-operative relation thereto.

21. In a photographic printing apparatus, relatively movable tubular printing members, each comprising a set of light transmitting images of symbols to be printed, a shield having an opening therein for supporting sensitive material in co-operative relation to said members while protecting part of said material from light, and means for directing light toward said members and shield.

22. In a photographic printing apparatus, 120 a chamber having a printing opening and an observation window in the walls thereof,

means for guiding film past said printing opening, printing members each mounted in said casing to move past both said opening and said window, each member comprising 5 light transmitting images of symbols to be printed and auxiliary images of said symbols, said auxiliary images being regularly spaced from said light transmitting images to bring opposite the observation window an 10 auxiliary image which corresponds to the light transmitting image which is opposite the printing opening.

23. In a photographic printing apparatus, relatively movable tubular printing members, each comprising a set of light transmitting images of symbols to be printed, and a pathway for the film adjacent said members.

24. In a photographic printing apparatus, 20 a pathway for the film comprising supports for the edges of the film, a depressed central portion, said pathway having a printing opening in line with one of the supports, and a printing device in said opening.

25. In a photographic printing apparatus, a pathway for the film comprising supports for the edges of the film, a depressed central portion, rolls to maintain the film out of contact with said depressed portion, said pathway having a printing opening in line with 30 one of the supports, and a printing device in said opening.

26. In a photographic printing apparatus, a pathway for the film comprising supports 35 for the edges of the film, said pathway having a printing opening in line with one of said supports, and a printing device having elements movable in said opening to positions substantially flush with the surface of 40 the last mentioned support.

27. In a photographic printing apparatus, a pathway for the film comprising supports for the edges of the film and a depressed central portion, said pathway having printing 45 openings in line with a support, a printing device having movable printing elements in one opening, and a stationary printing plate in the other opening.

28. In a photographic printing apparatus, 50 relatively movable tubular printing members, each comprising a set of light transmitting images of symbols to be printed, and a presser foot for pressing the sensitive photographic material into contact with said members.

29. In a photographic printing apparatus, relatively movable tubular printing members, each comprising a set of light transmitting images of symbols to be printed, a 60 presser foot for pressing the sensitive photographic material into contact with said members, and mechanism for alternately moving said members and said presser foot, the time of operation of said members being long rel-

ative to the time of operating said presser 65 foot.

30. In a photographic printing apparatus, relatively movable printing members, each comprising a set of light transmitting images of symbols to be printed, a presser 70 foot for pressing the photographic sensitive material against said members, and mechanism for operating said members and said presser foot, said mechanism being adjustable to vary the time during which the 75 presser foot operates.

31. In a photographic printing apparatus, a tubular bearing having a light transmitting area in the wall thereof, a relatively movable printing member comprising a set 80 of light transmitting images of symbols to be printed, said member being movably supported on said bearing to bring said images successively over said area, and a presser foot for pressing the sensitive photographic material against said member and toward said bearing.

32. In a photographic printing apparatus, a plurality of printing rings provided with a series of plane peripheral aligned facets 90 and with openings therethrough leading to said facets, each opening containing a light transmitting image of a symbol to be printed, and a presser foot having a plane face mounted to press sensitive material on to 95 said facets.

33. In a photographic printing apparatus, a plurality of relatively movable tubular printing members, each comprising a set of light transmitting images of symbols to be 100 printed, a pathway having an opening in which said members move, and a presser foot for pressing the sensitive photographic material onto the portion of said members in 105 said opening.

34. In a photographic printing apparatus, a plurality of relatively movable tubular printing members, each comprising a set of light transmitting images of symbols to be 110 printed, a pathway having an opening in which said members move, a presser foot for pressing the sensitive photographic material on to the portion of said members in 115 said opening, and driving means for intermittently operating said members and said presser foot, said means being adjustable to vary the time of operation of said presser foot.

35. In a photographic printing apparatus, a pathway for the film, comprising supports 120 for the edges of the film and a depressed central portion, said pathway having a printing opening in line with a support, a printing device having movable printing elements in 125 said opening and substantially flush with said support, and a presser foot for pressing the sensitive photographic material toward said support and elements.

36. In a photographic film contact printing apparatus, a printing device including an intermittently moving printing element, a presser foot for intermittently clamping the film against the element, and mechanism for operating the element and presser foot in timed relation. 65
37. In a photographic printing apparatus, a printing device including an intermittently moving printing element, a presser foot for intermittently and positively clamping the film against the element, and mechanism for operating the element and presser foot in timed relation. 70
38. In a photographic printing apparatus, a printing device including a movable printing element and a presser foot movable toward said element to press the film thereagainst, said presser foot comprising a movable arm and a pivoted foot detachably connected to said arm to be moved thereby, said foot when disconnected from said arm being adapted to be swung away from said printing element to permit access to the latter. 75
39. In a photographic printing apparatus, a series of tubular printing members each comprising a set of images of symbols to be printed, a light source, and means for directing a separate beam of light from said source to each member. 80
40. In a photographic printing apparatus, a series of tubular printing members, comprising a set of images of symbols to be printed, a light source, and adjustable means for directing a separate beam of light from said source to each member. 85
41. In a photographic printing apparatus, a series of relatively movable members each comprising a set of images of symbols to be printed, a light source, and reflecting means for directing a separate beam of light from said source to each member. 90
42. In a photographic printing apparatus, a printing device including a series of relatively movable members, each comprising a set of images to be printed, a light source, a mirror for laterally bending beams of light from said source, and a series of mirrors for directing each of said beams to a separate member. 95
43. In a photographic printing apparatus, a printing device including a series of relatively movable members, each comprising a set of images of symbols to be printed, a lamp, a casing for said lamp provided with an opening in one wall thereof, and reflecting devices for directing the light issuing through said opening from the lamp toward said members. 100
44. In a photographic printing apparatus, a printing device including a series of relatively movable members, each comprising a set of light transmitting images of symbols to be printed, a chamber containing said members, a lamp, a casing for said lamp provided with a window in one wall thereof opening into said chamber, and reflecting devices for directing the light issuing through said window from the lamp toward said members. 105
45. In a photographic printing apparatus, a tubular printing member having a series of light transmitting images thereon, a light source, and reflecting means for directing a beam of light from said source toward said images. 110
46. In a photographic printing apparatus, a tubular printing member, comprising images of light transmitting printing symbols, a light source external to said member, and means for directing light from said source into said member and toward said images. 115
47. In a photographic printing apparatus, a series of axially alined relatively movable tubular printing members, each comprising light transmitting images of symbols to be printed, a lamp, a case for said lamp provided with an opening in the wall thereof, a mirror for directing the light rays issuing through said opening into said members and substantially parallel to the axis thereof, and a set of staggered mirrors in said members for directing rays substantially outwardly toward said images. 120
48. In a photographic printing apparatus, a series of relatively movable tubular members each comprising a set of symbols to be printed, and a staggered series of mirrors in said members and at an angle to the axes thereof. 125
49. In a photographic printing apparatus, a printing device including a series of relatively movable tubular members, each comprising a set of images of symbols to be printed, a chamber containing said members, a lamp, a casing inclosing said lamp having a window opening into said chamber, a detachable mirror forming part of the wall of said chamber and directing light issuing through said window from the lamp toward the interior of said members, and a set of mirrors in said members for directing said rays outwardly toward said images. 130
50. In a photographic printing apparatus, a tubular bearing having a light transmitting area in the wall thereof, a movable tubular printing member comprising a set of light transmitting images of symbols to be printed, said member being movably mounted on said bearing to bring said images successively over said area and a mirror in said tubular bearing inclined to the axis thereof, and means for sending light toward said mirror. 135
51. In a photographic printing apparatus, a pathway for the film, a light source, rela-

5 tively movable printing elements comprising images of symbols to be printed, said elements being movable between said light source and said pathway, a slotted shutter 5 movable between said light source and said pathway, and means for operating said shutter intermittently in one direction only.

10 52. In a photographic printing apparatus, a pathway for the film having an opening 10 therein, a light source, printing elements movable between said light source and said opening, a tubular slotted shutter movable between said light source and said opening, and mechanism for intermittently moving 15 said shutter to bring a slot past said opening.

20 53. In a photographic printing apparatus, a pathway for the film, movable printing members each comprising a set of images of symbols to be printed, an intermittent shutter adjacent thereto, a light source, and reflecting devices for directing light from said source toward said shutter, printing members, and pathway.

25 54. In a photographic printing apparatus, a series of relatively movable members, each comprising a set of images of symbols to be printed, a light source, and means for directing a separate beam of light from said source to each member.

30 55. In a photographic printing apparatus, a tubular light printing member having a series of light transmitting images of symbols to be printed, a light source, reflecting 35 means for directing light from said source toward said images, and a shutter between said source and said member.

40 56. In a photographic printing apparatus, a tubular bearing having a light transmitting area in the wall thereof, a tubular printing member comprising a set of light transmitting images of symbols to be printed, said member being movably mounted on said bearing to bring said images successively over said area, and a shutter having an opening therein movable in said bearing across said area.

45 57. In a photographic printing apparatus, a tubular bearing having a light transmitting area in the wall thereof, a tubular printing member comprising a set of light transmitting images of symbols to be printed, said member being movably mounted on said bearing to bring said images successively over said area, a shutter having an opening therein movable in said bearing across said opening, and a lamp and reflecting devices for directing actinic light into said bearing and toward said shutter, area, and member.

60 58. In a photographic printing apparatus, a movable printing element comprising a set of symbols to be printed, means for sending actinic light toward said element, a shutter

between said means and element for intermittently passing said light during separate periods to said elements, and adjustable means to vary the length of said periods.

59. In a photographic printing apparatus, a relatively movable tubular printing element, comprising a set of light transmitting images of symbols to be printed, means for sending actinic light toward said element, a shutter between said means and element for intermittently passing said light during separate periods to said element, and operating mechanism for said shutter, said mechanism being adjustable to vary the length of said periods.

60. In a photographic printing apparatus, a movable printing element comprising a set of symbols to be printed, means for sending actinic light toward said element, a shutter between said means and element for intermittently passing said light during separate periods to said element, and mechanism for driving said shutter having an adjustably retarded element.

61. In a photographic printing apparatus, a movable printing element, comprising a set of symbols to be printed, means for sending actinic light toward said element, a shutter movable between said means and element, a continuously moving driving device, connections between said device and shutter for moving the latter intermittently, and adjustments in said connections whereby the speed of the shutter movement may be controlled.

62. In a photographic printing apparatus, a movable printing element, comprising a set of symbols to be printed, means for sending actinic light toward said element, a shutter movable between said means and element, and mechanism for alternately moving said element and said shutter, the movement of the element being slow relative to the movement of the shutter.

63. In a photographic printing apparatus, a movable printing element, comprising a set of symbols to be printed, means for sending actinic light toward said element, a shutter movable between said means and element, a mechanism for operating said element and shutter, said mechanism including a reciprocating device, and connections between said device, and said element, and said shutter, whereby the element is operated during the stroke of the device in one direction and the shutter is operated during the stroke of said device in the other direction.

64. In a photographic printing apparatus, a movable printing element, comprising a set of symbols to be printed, means for sending actinic light toward said element, a shutter movable between said means and element, a mechanism for operating said element and shutter, said mechanism including

a reciprocating device, connections between said device, and said element, and said shutter, whereby the element is operated during the stroke of the device in one direction and 5 the shutter is operated during the stroke of said device in the other direction, and means for adjustably retarding said device during its latter stroke.

65. In a photographic printing apparatus, 10 a movable printing element comprising a set of symbols to be printed, means for sending actinic light toward said element, a shutter movable between said means and element, a presser foot for pressing the photographic 15 sensitive material toward said element, and operating mechanism for moving said element while said presser foot and shutter are stationary and for operating said presser foot and shutter while said element is stationary.

66. In a photographic printing apparatus, relatively movable tubular printing members, each comprising a set of light transmitting images of symbols to be printed, 25 means for feeding film across said members, and driving mechanism for operating said film feed and members in timed relation.

67. In a photographic printing apparatus, relatively movable tubular printing members, each comprising a set of light transmitting images of symbols to be printed, a device for feeding film across said members, means for intermittently sending actinic light toward said film through said members, 30 and mechanism for operating said members, device, and means in timed relation.

68. In a photographic printing apparatus, a printing station, feeding means for advancing the film intermittently past said 40 printing station, a numbering device for successively presenting to said station a series of consecutive printing numbers, and mechanism connected to said feeding means for operating said numbering device to present said numbers in consecutive decreasing 45 order to said station as the film is advanced.

69. In a photographic printing apparatus, relatively movable tubular printing members, each comprising a set of light transmitting images of symbols to be printed, a presser foot for pressing photographic sensitive material toward said members, means for directing actinic light toward said material through said members, a 50 shutter, and driving mechanism for operating said members, presser foot, and shutter in timed relation.

70. In a photographic printing apparatus, 60 a series of relatively movable printing members, each comprising a set of light transmitting images of symbols to be printed, a device for feeding a film across said members, a presser foot for pressing said film

against said members, and means for operating said members, device, and presser foot in timed relation.

71. In a photographic printing apparatus, a movable printing element comprising a set of symbols to be printed, means for intermittently directing actinic light toward said element including a movable shutter, a pivoted member for operating said shutter, means for intermittently giving a quick turn to said member, and means for positively 75 limiting the amount of such turn.

72. In a photographic printing apparatus, a movable printing element comprising a set of symbols to be printed, means for intermittently directing actinic light toward 80 said element, a presser foot for intermittently pressing photographic sensitive material toward said element, a pivoted member for operating said means, a presser foot, and means for intermittently giving a quick 85 turn to said member, and means for positively limiting the amount of such turn.

73. In a photographic printing apparatus, a movable printing element, comprising a set of symbols to be printed, driving means 90 for said element including an oscillating shaft, means for intermittently directing actinic light toward said element including a movable shutter, a shaft for operating said shutter movable intermittently in one 95 direction, and operative connections between said shafts.

74. In a photographic printing apparatus, a movable printing element, comprising a set of symbols to be printed, driving means 100 for said element including an oscillating shaft, means for intermittently directing actinic light toward said element including a movable shutter, a shaft for operating said shutter movable intermittently in one direction, and means for operating said shafts 105 to alternately operate said element and said shutter.

75. In a photographic printing apparatus, a movable printing element, comprising a set of symbols to be printed, a presser foot for pressing sensitive photographic material toward said element, driving means for said element including an oscillating shaft, means for positively actuating said presser 110 foot including a shaft intermittently driven in one direction, and connections between the shafts for actuating them in timed relation.

76. In a photographic printing apparatus, an endless printing element, comprising a series of light transmitting images of symbols to be printed, driving means for moving said element step-by-step in one direction, a device preventing movement of said 120 element in the other direction, said means, device, and element being connected to permit manual movement of said element in 125

said first mentioned direction independently of said means and device, and means for sending light intermittently toward said images.

- 5 77. In a photographic printing apparatus, a set of relatively movable endless printing elements, each comprising images of consecutive numerals from 0 to 9 inclusive, a printing station past which said elements 10 are mounted to move intermittently, one numeral of each element being located at said station during the interval of rest, pawl and ratchet driving mechanisms, one

for each element, for moving said elements intermittently in one direction, pawl devices 15 for preventing movement of said elements in the other direction, said driving mechanism and said pawl devices allowing manual movement of said elements in the first named direction, whereby any numeral on any element may be rapidly brought to the printing station independently of said driving mechanism and said pawl devices.

Signed at Rochester, New York, this 10th day of May 1918.

JOHN G. JONES.
